[57] CLAIM

The ornamental design for an extendible automotive
ashtray reflector, as shown and described.

DESCRIPTION

FIG. 1 is a front elevational view of an extendible auto-
motive ashtray reflector, showing my new design;

FIG. 2 is a left side elevational view thereof;

FIG. 3 is a right side elevational view thereof;

FIG. 4 is a top plan view thereof;

FIG. 5 is a rear elevational view thereof; and

FIG. 6 is a bottom plan view thereof.

The reflector pattern seen in FIG. 1 is understood to
repeat uniformly and cover the entire surface.
